UNITED STATES PATENT OFFICE.

ROBERT L. JOHNSON, OF HANLEY, ENGLAND.

DESIGN FOR A COVERED DISH.

SPECIFICATION forming part of Design No. 25,385, dated April 14, 1898.

Application filed January 10, 1898. Serial No. 575,036. Term of patent 31 years.

To all whom it may concern:

Be it known that I, ROBERT L. JOHNSON, a subject of the Queen of Great Britain, residing at Hanley, Staffordshire, England, have 5 invented and produced a new and original Design for Covered Dishes, of which the following is a specification, reference being had to the accompanying drawings, forming a part thereof, in which—

10 Figure 1 is a plan view of the cover of the dish, and Fig. 2 is a side elevation of the body.

The leading feature of the design consists 15 in the handle for the cover A, together with the surface decoration of the same, and in the surface decoration of the body of the dish B. The handle *a* of the cover of the dish is 20 of scroll pattern and of a twisted design, approximating somewhat in general contour the letter S, with the central or loop portion extending transversely of the cover, the body of the handle being raised from the surface of the cover, and its ends apparently disappear in the cover. The handle is practically 25 surrounded by scroll figures, apparently rising from the upper surface of the cover.

The body B of the dish at its sides is divided into panels by means of scroll figures *b*, approximating the shape of a cornucopia or horn of plenty. The minor features of the design 30 consist of the handles *b'* appearing at the ends of the body, which are of a scroll character, and appear as connected scrolls bowed outwardly and in a measure upwardly from the body, and, further, in the formation of the 35 bottom or base of the body, which is of scalloped decorative contour, and the margin of the cover is likewise scalloped in general contour, and is decorated with a marginal band, and decorative panels appear between the 40 edge of the cover and said band at sundry points.

I claim—

A design for a covered dish, substantially as shown and described.

ROBERT L. JOHNSON.
